FIG. 5

UNITED STATES PATENT OFFICE

2,655,026

COMBINATION LOCK

Harrison B. Syler, Los Angeles, Calif.

Application October 9, 1951, Serial No. 250,537

14 Claims. (Cl. 70—146)

1

The invention relates to keyless or combination locks.

An important object of the invention is to provide a combination lock which permits manipulations from either side of a door in order to unlock the door, and the keyless lock may be manipulated from either side of the door in order to lock it.

Another important object is to provide a keyless lock comprising but few parts and none of them complicated.

A further important object is to provide a combination lock including but one resilient member, preferably in the form of an expansion helical spring, which is easily removed for replacement.

Yet another object is to provide such a lock which requires no opening in the door to which it is secured, other than a readily-bored hole, quite similar to that provided for a conventional lock spindle.

Since the lock of this invention is relatively inexpensive, due to its few and readily machined parts, it may be employed on screen doors, usually provided simply with latches or hook-and-eye closure fasteners, yet the dialing of the new lock is such that small children will not be apt to be able to manipulate the lock in order to unlock the door.

A further object is to provide a combination lock having means to manually change the combination when desired.

Other objects and advantages of the invention will be apparent during the course of the following detailed description of the invention, taken in connection with the accompanying drawings, forming a portion of this disclosure, and in which drawing:

Fig. 1 is a vertical longitudinal section, substantially on the line 1—1 of Fig. 2, of one form (single dial) of the new combination lock with the parts in a locked position, and a fragmentary transverse vertical section of a closure, as a door, to which it is attached.

Fig. 2 is a vertical transverse section of the lock substantially on the line 2—2 of Fig. 1.

Fig. 3 is a perspective view of a special sleeve and dial or flange of the new lock.

Fig. 4 is a view, somewhat along the lines of Fig. 1 with the parts of the lock in an unlocked position.

Fig. 5 is a vertical longitudinal section of another form of the new keyless lock, applicable to inwardly-opening doors.

Fig. 6 is a fragmentary vertical longitudinal

section of a combination two-dial form of the new lock.

Fig. 7 is a perspective of the two dials of the lock of Fig. 6.

5 Fig. 8 is a vertical section, substantially on the line 8—8 of Fig. 6.

In the drawings, wherein for the purpose of illustration are shown three forms of the invention and wherein similar reference characters 10 designate corresponding parts throughout the several views, the letter A designates my single-cylinder combination lock; B, a form adapted to inwardly-opening doors, C, the two-dial form thereof, D, E, and F closures, as doors, to which the locks may be secured, and G, a closure frame, as a door frame.

Referring to Figs. 1 to 4 inclusive, the new single-cylinder combination lock A includes the lock housing 10 having suitable axially-aligned 20 openings in opposite side walls 11 and 12 for the spindle 30, suitable openings in opposite end walls 13 and 14 for the bolt 25, and an elongated opening in the upper wall 15 for a portion of means 65 for withdrawing or retracting the bolt

25. The opening in the wall 14 may be closed by the thimble 16 which projects outwardly of the wall 14, and has an air vent opening 17 in its outward portion while its inward portion may be provided with exterior screw threads to 30 operate with the interior screw threads of a collar 18 forming a part of the wall 14. The thimble 16 slidably accommodates an end portion of the bolt 25 to be subsequently described. Suitable means 19 as screws, extending through 35 openings in conventional flanges 20 of the housing, may be employed to secure the housing 10 to a door D.

The bolt 25, best shown in Fig. 2, is preferably 40 of generally cylindrical shape but with the conventional end portion 26 adapted to enter the keeper opening in the lock strike of the door frame G. It is provided with means to receive the free end of a set screw (to be described) and this means may be the wall of a depression 27 intermediate the ends of the bolt. An expansion helical spring 28, with one end bearing 45 against the inner end of the thimble 16 and its other end bearing against a projection such as the collar 29 about the periphery of the bolt 25 tends to shove the bolt to a door locking position when the collar is secured to the bolt as will be described.

Referring mainly to Fig. 1, the spindle 30 may 50 be cylindrical and the knobs 31 and 32 are mounted, as by set screws 33 and 34 to the outer

55

end portions of the spindle. The knob 32 which may be termed the inner knob, may be of conventional construction, but the knob 31 has an enlarged socket so that a portion of the new locking means or mechanism 35 may be accommodated therein, as will be next described.

The new combination locking mechanism or means 35 includes as best shown in Fig. 1 but also in Fig. 4, a special sleeve 36 encircling and secured to the spindle 30, as by the set screw 33 extending through a small opening in the forward end portion of the sleeve 36 and this sleeve is disposed within the socket of the door knob 31. The sleeve 36 has a narrow lug or projection 37 secured to it to project outwardly from its outer periphery and provided to slide into and out of a slot in the end portion of a second special sleeve 38 to be next described.

Still referring to Figs. 1 and 4, but also to Fig. 3, the locking mechanism 35, includes a second special sleeve 38. This sleeve is elongated and extends through a suitable opening in the door D, adapted to snugly but rotatably accommodate it, and its opposite end portions project from either side of the door. The outer end portion 39 projects considerably from the outer face of the door and its free end part is provided with a plurality of spaced-apart short radial slots 40 and one longer slot 41, all opening to the edge 42 of the sleeve 38. The slots are of a size to accommodate a portion of the lug 37. This end part extends into the socket of the knob 31 and is outwardly of the sleeve 36. Normally, the lug 37 is disposed outward of but quite closely adjacent the edge 42. Intermediate the ends of the sleeve 38 is a ring 43 which may be fixedly secured to the sleeve 39 as by a set screw 44. The ring has, on its outer surface or periphery, a plurality of spaced-apart graduation lines 45 and other indicia, as the letters 46. At the other end portion of the sleeve 38 is a preferably wide outwardly-extending flange 47 having a plurality of spaced-apart indicators 48 extending radially from its periphery. These may be slots, grooves, etched lines or the like, provided with indicator symbols, as the indicia 49. Associated with the indicia upon the ring 43 is an index or pointer 50 having a bracket portion adapted to be secured to the outer face of the door D as by a screw 51 with the longitudinal axis of the pointer 50 substantially vertical and the pointer pointing downwardly to the uppermost of the indicia. Additionally, there is a preferably substantially like pointer or index 52 with its bracket portion secured, as by a screw 53, to the inner face of the door D and with its longitudinal axis also substantially vertical but the pointer points upwardly to the lowermost of the indicators 48. Since the flange 47 is accommodated between the inner face of the door D and the inner side face of the wall 12 of the lock housing 10, the means 19, as screws, to secure this housing to the door may be provided with spacers 54, whereby there is provided clearance for the flange so that it and the rest of the sleeve 38 may be rotated. So that rotation of the flange will not be impeded by a wooden surface in contact with a face (the inner face) thereof, I may provide a metallic perforated disc 55 preferably set into a slight recess 56 in the inner face of the door.

A portion of the locking mechanism 35 comprises an expansion helical spring 57 surrounding an intermediate portion of the spindle 30 substantially as in Fig. 1 with one end of the spring bearing against the sleeve 36 and the other end

bearing against a collar 58 slidably retained about the spindle 30. The collar 58 may be retained against movement towards the knob 32 as by upsetting the material of the sleeve 38 to provide a shoulder 59 extending toward the axial center of the sleeve 38. The collar 58 also functions to and in preventing rocking of the spindle 30.

Mounted (as by welding or soldering) upon the spindle 30 within the housing 10, is a lug or projection 60 with its longitudinal axis substantially paralleling the longitudinal axis of the spindle 30. The position of this lug 60 when the portion 26 of the bolt 25 is within the opening in the strike plate (i. e. when the door is locked) is as in Fig. 2, with the lug 60 contacting, at one of its side faces, the collar 29 and contacting, at its other face, a stop 61 which may be a pin bridging and secured to the walls 11 and 12 of the housing 10. As may be appreciated from Fig. 2, rotation of the spindle 30 clockwise will unlock the door. When the lock is in the locked position (as in Fig. 1) a portion of the lug 60 contacts the inner face of the wall 12 and limits or prevents longitudinal movement of the spindle 30 in one direction; longitudinal movement in the other direction being prevented by engagement of lug 37 with the outer end portion 39 of the sleeve 38. Also a second portion of the lug 60 is positioned within a notch in the wall 12 in order to prevent rotation of the spindle 30 in either direction.

Means 65 to effect retraction or withdrawal of the bolt end portion 26 from the keeper by manipulations from inside the door D, may be effected by grasping the outwardly projecting handle 66, which is secured to screw 67 and pushing the handle 66 to the right in Fig. 2, since the screw 67 extends through the collar 29 and into the depression 21.

It is now apparent that a person at the outside 40 of the door and knowing the certain indicia 46 upon the ring 43 which, when aligned with the pointer 50, will align the narrow lug 37 with the longer slot 41 may so align said narrow lug and longer slot and press the knob 31 away from him, and this will cause the lug 37 to enter the slot 41 and the spindle 30 to move longitudinally to the left as in Fig. 4, releasing the second portion of the lug 60 from the notch in wall 12 and enable him to rotate the spindle 30 to cause the lug 60 to push the collar 29 to the right in Fig. 2 and thus withdraw the bolt 25.

Because the ring 43 is retained by the set screw 44, it is now obvious that the ring may be rotated, after loosening the set screw 44, and then tightening it, in order to cause certain new indicia 46 to indicate, when properly oriented with the pointer 50, that the slot 41 is aligned with the lug 37.

A person at the inside can manipulate the new lock A by rotating the flange 47 until certain indicia 49 and an indicator 48 aligns with the pointer 52 whereupon the knob 32 is pulled, having the same effect as pushing the knob 31, and turned to unlock the door. It is preferred that the indicators 48 be slots, since this renders the flange 47 easier to rotate by the hand or a finger.

For doors which open inwardly, the combination lock B of Fig. 5 is applicable.

The lock housing 10 is substantially like the housing 10 except that the front side wall 71 has a lug-receiving slot 72 as well as an opening for a spindle 75 with the slot extending to the opening, and there is no opening in the upper wall 73, similar to that in the upper wall 15.

Additionally, the bolt structure 25 to 29 inclu-

sive is applicable to the lock B and similar reference characters are employed in Fig. 5.

The spindle 75 of the lock B as well as the outside knob 76 and inside knob 77 are different from those of the keyless lock A, and carry a part of the locking mechanism 78 for, intermediate its ends, but adjacent the outer portion of the spindle 75 containing the knob 76, the spindle fixedly mounts a radially extending spur or lug 79 substantially as shown in Fig. 5. Inwardly of and spaced from the lug 79, the spindle is provided with a shoulder 80 by longitudinally grooving a portion of the spindle, whereby a groove 81 is provided from the shoulder to somewhat inwardly of the end 82 of the spindle, as in Fig. 5. The flattened surface ends at a set screw 83 extending diametrically through the spindle with the screw 83 having a flattened longitudinally-extending portion providing a shoulder 82a.

The knob 76 has a spindle-end-accommodating socket and is removably secured to the spindle as by a set screw 85. At the door-facing end of the knob 76, the socket is enlarged in diameter and at the mouth of the enlarged socket 86 there is a lug 87, preferably of metal fixedly secured to the knob in any approved way and being a part of the locking mechanism 78.

The inside knob 77 has a socket to receive the other end portion 82 of the spindle and this socket is enlarged at its mouth portion 88 to accommodate portions of structure to be described. A set screw 88a secures the knob 77 to a sleeve 111 subsequently described. It will be noted that the knob 77 is normally spaced from the housing 70, whereby it may be pushed toward the door E.

Deposited about a part of the outer portion of the spindle 75, but not secured thereto, is a ring 89 having a flange 90 extending outwardly from its periphery and a skirt portion 91 extending from the opposite end of the ring. The ring 89 is provided with a slot 92 to accommodate the lug 79.

Outwardly of the ring 89 and its skirt portion 91 and within the plane of the periphery of the flange 90, is an elongated special sleeve 95, considerably like the sleeve 38 and this sleeve is fixedly secured to the outer periphery of the skirt portion 91, by suitable fasteners as headed rivets 96, this sleeve mounting a ring 97 rotates on the outer periphery of the skirt portion 91. However, the ring 97 cannot reciprocate independently of the ring 89 and its skirt portion 91 since a fixed ring 103, to be subsequently described, prevents reciprocation in one direction and the flange 90 prevents it in the opposite direction. Like the ring 43, the ring 97 contains suitable spaced apart graduation lines and other indicia, as letters substantially like the lines 45 and letters 46 of the ring 43. The ring 97 has a peripheral groove 98 intermediate its ends adapted to contain the lug 87 and a slot 99 extending from the groove toward the flange 90, also adapted to contain the lug 87. A pointer 100 substantially like the pointer 50 is secured to the door E as by a screw 101 which, in this case, may also pass through a rose plate 102. Freely rotatable with the sleeve 95 between the ring 89 and rose plate 102 is another ring 103 quite like the ring 43 since it is secured to the skirt portion 91 (in this case as by the rivets 96) and its carries indicia like that of the ring 43, for cooperation with the pointer 100. The ring 103 abuts the ring 97.

Like the special sleeve 38, the special sleeve 95 75 117 and when the two slots 117 and 124 align,

has a rather wide peripheral flange 104 at its end where it extends outwardly of the inner face of the door E, and this flange, substantially akin to the flange 47, contains a plurality of spaced apart slots like the slots 48 of the flange 47. The sleeve 95 has the equivalent of the slot 41 in the provision of the slot 92 which is in the ring 89 rigid with the sleeve 95.

A portion of the combination locking mechanism 78 also comprises means 110 permitting an operator, at the inside, to open the door E despite the set keyless lock. This is an elongated sleeve 111 about the inner end portion of the spindle 75. This sleeve is fixed to the knob 77 by the set screw 88a and abuts, as its knob-facing end, the set screw 83. It carries a radially projecting lug 112 adapted to slide in and out of the slot 72 in the wall 71 of the housing 70. When positioned as in Fig. 5, the lug 112 cannot move, since it is within the slot 72 and it, in turn, prevents movement of the collar 29 of the bolt structure (in the case of the collar 29 of the bolt structure for the keyless lock B, the screw 113 is not connected with a handle, like the handle 66, and does not project through the upper wall 73) to cause retraction of the bolt. However, when the knob 77 is pushed, the lug 112 will slide out of the slot 72 and will permit retraction of the bolt.

The sleeve 111 has a longitudinally-extending radially-projecting rib 114 extending from the inner surface of the sleeve toward its longitudinal axis and this slides in the groove 81 in the spindle 75.

An expansion helical spring 115 extends about an intermediate part of the spindle 75, bears at one end against the inner end of the sleeve 111, and bears at its other end against a washer 116 about the spindle and bearing, in turn, against the end part of the free end of skirt portion 91 of the ring 89.

In order to lock the closed door B, from the outside, the operator simply rotates (tumbles) the rings 97 and 103 when parts are in their positions as in Fig. 5. To unlock the door from the outside, the ring 97 must be rotated to bring the determined indicia upon the ring 97 uppermost which indicia aligns with the slot 99 and rotates the ring 103 so that the determined indicia thereon is aligned with the pointer 100 and this corresponds with the aligning of the slot 92 and lug 79. The knob 76 may now be pulled thus drawing the lug 112 out of the slot 72 and when the knob is then turned, the bolt will be withdrawn.

From the inside, by simply pressing on the knob 77 the lug 112 will be caused to leave the slot 72 and the bolt may be retracted.

In order to tumble the ring 103 so that an unauthorized person cannot pull open the knob 76 and turn it, in order to open the door E, an operator on the inside simply twirls the flange 104 which misaligns the slot 92 and lug 79. In either case the knob 76 cannot be pulled without knowledge of the combination.

Referring now to Figures 6, 7 and 8, the two-cylinder combination lock C is, generally, exactly like the lock A except that in addition to the sleeve 115 somewhat like the sleeve 38 of the lock A, there is an inner sleeve 120 with a flange 121 not quite so great in diameter as the flange 116 rotatable over the face of the flange 116 and provided with suitable indicia 122, as numerals and graduations, as slots 123. The free end of the sleeve 120 has a long slot 124 like the slot

as in Fig. 8, the lug or projection 37 may enter them, thus permitting turning of the knob 31.

The inner sleeve has a shoulder 125 like the shoulder 118 with the shoulder 125 extending into the hollow of the shoulder 59 and rotatable therein.

In addition to the ring 43' with its indicia 46 and graduations 45, there is provided a slot or opening 119 in the sleeve 115 close to the ring 43 and graduations 126 and numerals 127 about the outer periphery of the sleeve 120 showing through the slot 119. The slot 119 is large enough to readily receive the ball of a finger or the thumb in order to rotate the sleeve 120, and its edges are preferably bevelled.

Knowing the indicia (as numerals or letters) which will align, when properly aligned with the pointer 50, the slots 117 and 124, the operator will rotate the sleeves 115 and 120 to effect this or if, on the other side of the door, will manipulate the flanges 116 and 121 to effect the same result by aligning the proper indicia with the pointer 52.

The closure of door D has an opening 130 to receive the sleeve 38, while the closure E has an opening 131 to receive the sleeve 95, and the closure F has an opening 132 to receive the sleeves 115 and 120. The frame G of Fig. 2 has a conventional apertured lock strike 133 and recess 134 to receive the conventional end portion 26 of the bolt 25. Other than that these several openings 130, 131 and 132 are somewhat larger in diameter than those of conventional openings in doors to receive conventional spindlers, the doors associated with the locks A, B and C, require no modifications.

Various changes may be made to the forms of the invention herein shown and described without departing from the spirit of the invention or scope of the claims.

What is claimed is:

1. A combination lock for a two-sided closure, including a lock bolt housing; a lock bolt slidable inwardly and outwardly of said housing; means adapted for securing said lock housing to one side of the closure and spaced therefrom; means normally throwing said bolt into an outward position; retraction means to retract said bolt; combination lock means selectively retaining said retraction means against movement and permitting movement of said retraction means, adapted to be operated from the other side of said closure and including a rotatable sleeve; and means for operating said combination lock means from said one side of the closure, including a dial secured to said sleeve and adapted to extend over a portion of said one side, said dial being disposed adjacent said housing and adapted to be located between said housing and said one side and extending outwardly of the plane of said housing.

2. A combination lock according to claim 1 characterized in that said dial has an outer periphery and is notched from said periphery inwardly toward the axes of rotation of said dial and sleeve.

3. A combination lock according to claim 1 characterized in that said retraction means includes a reciprocable spindle, said sleeve extends about a portion of said spindle and is fixed against longitudinal reciprocation.

4. A combination lock for a two-sided closure, including a lock bolt housing; means adapted for securing said housing to one side of said closure and spaced therefrom; a lock bolt slidable in-

wardly and outwardly of the housing; means normally throwing said bolt into an outward position; retraction means to retract said bolt, including a rotatable and reciprocable spindle; combination lock means selectively retaining said retraction means against movement and permitting movement of said retraction means, adapted to be operated from the other side of said closure, including a rotatable sleeve surrounding a portion of said spindle; resilient means urging said spindle in one longitudinal direction; and means, cooperating with said housing, restraining said sleeve against movement longitudinally of said spindle, including a rotatable flange fixed to said sleeve and disposed closely adjacent said housing and adapted to be located between said one side of said closure and said housing.

5. A combination lock according to claim 4 characterized in that said flange is notched at its periphery and extends outwardly of the plane of said housing.

6. A combination lock according to claim 4 characterized in that said sleeve has an inwardly projecting shoulder, said resilient means is an expansion helical spring surrounding a portion of said spindle, and there is provided an abutment for one end of said spring with said abutment bearing against said shoulder.

7. A combination lock according to claim 4 characterized in that said combination lock means also includes a member fixed to said spindle and provided with an outwardly-extending lug, and said sleeve is provided with a slot constructed and arranged to receive said lug upon shifting of said spindle against the force of said resilient means.

8. A combination lock according to claim 4 characterized in that said combination lock means also includes a lug rigid with said spindle and disposed within said lock housing, and a member fixed to said spindle and provided with an outwardly-extending lug, and said sleeve is provided with a slot constructed and arranged to receive the last-mentioned lug upon shifting of said spindle against the force of said resilient means, and said lock bolt is provided with a projection rigid therewith and disposed in the path of travel of said lug within said lock housing when said spindle is reciprocated and rotated for retracting said bolt.

9. A combination lock according to claim 4 characterized in that said combination lock means also includes a member fixed to said spindle and provided with an outwardly-extending lug, said sleeve is provided with a slot constructed and arranged to receive said lug upon shifting of said spindle against the force of said resilient means, and said retraction means includes a knob having a socket accommodating and concealing said lug and said slot and a fastener securing said knob to said spindle.

10. A combination lock according to claim 4 characterized in that said combination lock means also includes a member fixed to said spindle and provided with an outwardly-extending lug, with an end of said resilient means bearing against an end of said member, said sleeve is provided with a slot constructed and arranged to receive said lug upon shifting of said spindle against the force of said resilient means, and said retraction means includes a knob having a socket accommodating and concealing said lug and said slot and a fastener securing said knob to said spindle.

11. A combination lock according to claim 4 characterized in that said combination lock means includes a ring extending about and secured to a portion of the outer periphery of said sleeve and provided with combination lock indicia, and a pointer adapted to be secured to said other side of said closure for pointing to the uppermost of said indicia.

12. A combination lock according to claim 4 characterized in that said lock bolt has a forward end portion and a rearward end portion, said lock housing has an opening in a wall thereof slidably accommodating a part of said rear end portion and is provided with a detachable thimble extending outwardly of said housing at said opening and accommodating a part of said rear end portion, and said means normally throwing said bolt into a locking position includes an expansion helical spring with one end thereof bearing against the inner end of said thimble, the diameter of said expansion helical spring being less than the diameter of said opening in said housing.

13. A combination lock according to claim 4 characterized in that said combination lock means includes a lug fixedly secured to said spindle and extending radially therefrom, a ring within and fixedly secured to said sleeve and having a slot disposed, when said sleeve is rotated, in the path of travel of said lug upon reciprocation of said spindle, and a peripheral flange at the end of said ring remote from said resilient means, a knob secured to said spindle

and having a socket with a lug projecting from said knob into said socket, a ring disposed upon a portion of the outer periphery of said sleeve and secured to said sleeve, provided with a groove receiving said last lug and a slot extending from said groove toward said flange and disposed, when said sleeve is rotated, in the path of travel of said last lug when said spindle is shifted to cause said first lug to enter said first slot.

14. A combination lock according to claim 4 characterized in that said combination lock means includes a second sleeve rotatable within the first sleeve, and there is provided means cooperating with said housing restraining said second sleeve against movement longitudinally of said spindle, including a rotatable flange rigidly fixed to the second-mentioned sleeve, disposed outwardly of the first-mentioned flange and closely adjacent said housing, and being of lesser diameter than the first-mentioned flange.
